FIG. 6.

10 INVENTION
Earl H. Sherbondy
BY *Albert H. Young*
Captain, 25 Sept. 1912
ATTORNEY

UNITED STATES PATENT OFFICE.

EARL H. SHERBONDY, OF CLEVELAND, OHIO.

TURBINE NOZZLE-RING.

1,310,681.

Specification of Letters Patent. Patented July 22, 1919.

Application filed May 14, 1918. Serial No. 234,553.

To all whom it may concern:

Be it known that I, EARL H. SHERBONDY, a citizen of the United States, residing at Cleveland, in the county of Cuyahoga and 5 State of Ohio, have invented certain new and useful Improvements in Turbine Nozzle-Rings, of which the following is a specification.

This invention relates to a turbine nozzle ring, more particularly to one that is to be used in connection with a turbine that is operated by the waste gases from an internal combustion engine.

It is an object of the invention to produce 15 a nozzle ring which is susceptible of fairly rapid production, and which will withstand the high temperatures met with in a gas operated turbine.

It is a further object of the invention to 20 provide a nozzle ring which may be readily mounted onto the inlet chamber for the gases that operate the turbine.

It is another object of the invention to 25 provide a nozzle ring with a series of peripheral inlet openings and a corresponding series of side outlet openings.

It is another object of the invention to 30 provide a double discharge nozzle ring, that is to say, one which will discharge gas on both sides to operate two turbine wheels, and which is accordingly positioned between the turbine wheels. This double discharge ring is also provided with peripheral inlet openings, one set of peripheral openings taking in gas for discharge to one turbine wheel, and the other alternate peripheral openings taking in gas for discharge onto the other wheel.

Other objects and advantages will appear as the description proceeds.

Referring to the drawings which are 40 more or less diagrammatic, Figure 1 is a top view of the single discharge nozzle ring; Fig. 2 is a side view of the same; Fig. 3 is a section on the line 3—3 of Fig. 2; Figs. 4 and 5 are sectional views, respectively, on the lines 4—4 and 5—5 of Fig. 2; Fig. 6 is a top view of the double discharge nozzle ring; Fig. 7 is a view of the single discharge 45 nozzle ring in position in relation to the turbine; and Fig. 8 is a view of the double discharge ring positioned in relation to the turbine.

The nozzle ring 1 is made from a solid 55 annular blank of material which will withstand the high temperatures met with in a

gas operated turbine. This annular blank is rectangular in cross section. The series of nozzles with peripheral inlets and side outlets may be cut in this ring in a number of different ways, and may be of a number of different shapes, and may evidently be made by a number of different methods. The gist of the invention is in having peripheral inlets for the gas and side outlets. 60 As shown in Fig. 1, the nozzle ring 1 has cut into the inlet opening ABCD, here shown as rectangular. This opening, however, could be of any desired shape, for instance—elliptical. The discharge opening 70 for the inlet opening ABCD is shown in Fig. 2 at C'B'A'D'. The nozzle passage itself, indicated at N, is four-sided, being defined by the four walls that intersect on the lines AA', BB', CC', DD'. 75

It will be noted that the nozzle passage N is cut through the ring 1 in such a direction as to deliver the gas in the same direction as the direction of rotation of the turbine wheel, as indicated by the arrow in Fig. 1.

The nozzle passage N is preferably cut in such a way that its cross sectional area decreases toward the outlet, this decrease in the nozzle area serving to impart additional velocity to the outgoing gas.

In one method of manufacture, and in order to facilitate the cutting of the nozzle passage N, the nozzle blank may be profiled all the way around on the curved line 2—3, Fig. 5. The line 2, 2, Fig. 1, representing 80 the inner edge of the profiled portion, goes back far enough from the edge of the blank 1 to be coincident with the line DC, representing the adjacent edge of the inlet opening ABCD. The line 3, 3, representing the 85 other edge of the profiled portion, is at such a distance from the upper edge of the original blank as to be coincident with the line D'A', Fig. 2. The removal of the section of metal 2, 3, 4, is to facilitate the machining 90 operations in cutting the passage N. After the passage N has been cut, a profile ring 5 is suitably fastened in position in this cut away portion. This profile ring 5 has a series of apertures 5' cut into, which apertures 5' register with the several discharge openings C'B'A'B'. 100

Referring now to Fig. 6, a substantial duplication of the arrangement in Fig. 1 is shown. The body 6 of the nozzle ring is 110 made from a blank somewhat thicker than the blank 1, in view of the fact that a double

set of nozzles are to be cut therein. The nozzles in this case are cut in substantially the same way as described in connection with the other figures, with this difference, however, that one series of the nozzles discharges the gas to one side of the wheel, and the other series of nozzles, which are positioned between the members of the first series, discharge gas to the other side of the wheel.

10 7 and 7' indicate the peripheral inlet passageways for two of the nozzles of one series, and 8 indicates the inlet opening of one of the series of nozzles that delivers gas on the other side of the turbine ring. The gas taken in through the nozzles 7 and 7' is delivered through the outlet openings 9 and 10, respectively, on one side, while the gas taken in through the opening 8 is discharged through the outlet openings 11 on the other side onto the other wheel. Other nozzles with inlet and outlet openings similar to 7 and 9, respectively, are positioned all the way around the nozzle ring 6, and other nozzles with inlet and outlet openings similar to 8 and 11, respectively, are positioned all the way around the nozzle ring, the second series being alternately placed with respect to the first series. In the course of manufacture, the blank 6 is profiled on both sides, as was done in the case of the single discharge ring, and the profiled portions filled with profile rings 12 and 13, respectively, these two profile rings being provided with the necessary apertures registering with the openings 9, 10, etc. on one side, and the series of openings 11 on the other side, respectively.

Referring now to Fig. 7, the nozzle ring 1 is positioned adjacent a turbine wheel 14, provided with the usual buckets 15, the turbine turning with a shaft 16. The nozzle ring 1 is supported by annular casing elements 17 and 18, forming an exhaust inlet chamber 19. The outer edges of the nozzle ring are supported between the two elements 17 and 18, so that the periphery of the nozzle ring faces into the chamber 19. The elements 17 and 18 are of a volute form, so as to give a volute chamber to uniformly distribute the incoming gas around the pe-

riphery of the nozzle ring. Associated with 50 the casing element 17 and the turbine, are casing elements 20 and 21, which define between them an exhaust chamber 22, into which the gas is discharged after leaving the buckets of the turbine. Inlet openings 55 ABCD open into the chamber 19, and the outlet openings C'B'A'D' open adjacent to buckets 15 of the turbine.

Referring now to Fig. 8, two turbine wheels 23 and 24, provided with buckets 23' and 24' are clutched together to turn on a shaft 25. The double discharge nozzle ring 6 is positioned between these two wheels 23 and 24, and has associated therewith casing elements 17' and 18', which define a volute chamber 19' for the exhaust gases. The inlet openings 7, 7', etc., and 8, etc., open into the chamber 19', discharge openings 9 and 10 discharging gas onto one of the wheels 23 and 24, while the other series of discharge openings 11 70 discharge onto the other wheel. The gas leaving the turbine buckets 23' and 24' passes into annular exhaust chambers 26 and 27, respectively, and escapes therefrom through 75 26' and 27', respectively.

It will be noted that the nozzle passageways are gradually and arcuated curved, presenting no sharp corners or abrupt turns, features minimizing steam friction and so aiding the flow of steam to the turbine buckets. 80

While I have illustrated possible embodiments of my invention, it should be understood, as pointed out in the first part of the specification, that the invention consists in making a nozzle ring with peripheral inlet 85 openings and side outlet openings, and that this inventive idea may be carried out in a number of different ways.

I claim—

A turbine nozzle ring for an axial flow 90 turbine, provided with a nozzle having a peripheral inlet and a side outlet, the nozzle passage presenting a gradual, arcuate curvature from inlet to outlet, said nozzle ring further being profiled on one side, and a profile ring seated on said profiled portion. 95

In testimony whereof I affix my signature.
EARL H. SHERBONDY.
